UNITED STATES PATENT OFFICE.

THEODORE HENRY KNORR, OF BRECKENRIDGE, COLORADO, ASSIGNOR OF ONE-HALF TO
HENRY A. RECEN, OF DENVER, COLORADO.

OVEN.

1,252,272.

Specification of Letters Patent.

Patented Jan. 1, 1918.

Application filed September 2, 1916. Serial No. 118,194.

To all whom it may concern:

Be it known that I, THEODORE HENRY KNORR, a citizen of the United States, residing at Breckenridge, in the county of Summit and State of Colorado, have invented certain new and useful Improvements in Ovens, of which the following is a specification.

This invention relates to an improvement 10 in ovens of stoves or ranges.

The object of this invention is to provide means for causing the bottom and trays to be moved outwardly upon the opening of the door, whereby access may be had to the 15 article being cooked for the purpose of examination or the removal from the oven without the danger of injury from burns and the like.

A further object is to provide means for 20 disengaging the actuating means of the trays from the oven, whereby the oven door may be readily opened without disturbing the trays when it is desirable.

The invention relates to still other novel 25 features of construction and the combinations of parts which will be hereinafter more fully described and pointed out in the claims.

In the accompanying drawings:

Figure 1, is a view in front elevation 30 showing the door closed;

Fig. 2, is a similar view of the door open;

Fig. 3, is a longitudinal vertical section showing the oven door in open position and the movable bottom in an extended position;

Fig. 4, is a similar view showing the movable bottom within the oven and the oven door closed;

Fig. 5, is an enlarged detailed view of the latch mechanism and associated parts.

40 A represents the oven, which may be of any approved shape, but which as shown in the drawing is practically square.

A movable bottom B is mounted within the oven A, and is adapted to rest and move 45 over the base or bottom 1. A telescoping lever consisting of parts 2 and 3 is pivotally connected to the rear side of the movable bottom B. A bracket 4 is connected to the rear side of the oven A in the uppermost 50 corner, and is provided with an elongated slot 5. Adapted to travel in the elongated slot 5 is a roller 6, which roller is connected to the outer free end of the telescoping member 3. The inner end of the telescoping members 2 and 3 is provided with rollers 7

and 8, each of which is adapted to engage the companion telescoping member, in order to reduce as much as possible the friction caused by the movement of the movable bottom B.

A crank shaft 9 is mounted upon the back of the oven A at the lower corner thereof, and an end of the shaft 9 is pivotally connected to the outer end of the telescoping member 2, so that upon the movement of the shaft, movement is imparted to the telescoping member 2 for causing the movable bottom to be moved either in the forward or rearward direction.

This crank shaft is substantially U-shaped, the lower portion 10 of which is adapted to extend horizontally along the bottom of the oven toward the outer right hand side, the outer end of which is then bent up, thereby forming another crank 75 shaft 11. A draw bar 12 is pivotally connected to the outer end of this crank shaft 11, and is adapted to extend horizontally along the outer wall of the oven toward the front thereof, the outer end being suitably supported upon a pin or roller 13, the said draw bar having at its outer end a suitable recess 14.

A bracket 15 is connected to the oven door C. This bracket is provided with a vertically arranged latch 16, which is received in a dove-tailed slot 17 of said bracket. The upper end of this latch is provided with a knob 18 adapted to register with the recess 14, when the latch is held in its uppermost 90 position by a cam 19 which is pivotally connected at 20 to the bracket 15.

It will thus be seen that upon the movement of the door the draw bar will be actuated, thereby causing the crank shaft to oscillate, the oscillation of the crank shaft causing the telescoping member 2 to be moved and imparting a movement to the movable bottom B, whereby it will be moved either in a forward or rearward direction, as disclosed in Fig. 4.

When the bottom is in the rearward position the said telescoping members 2 and 3 are adapted to telescope and assume a comparatively vertical position at the rear of the oven. The cam 19 is provided with a handle 21, which when in its lowermost position disengages the latch 16 from the draw bar 12. This arrangement permits of the movable bottom B being pushed manually 110

within the oven independent of the movement of the oven door.

When the latch 16 is in its lowermost position, it does not register with the recess 5 14 of the draw bar, thereby permitting the operator in this instance to open and close the oven door for inspection of the articles being baked without disturbing same, which is often desirable when baking.

10 It will thus be seen that with this construction, I have provided a means which can be arranged according to the desires of the operator; that is, the mechanism can be arranged in such a manner that the movable 15 bottom B will be forced outwardly from the oven, when the oven door is open, if it is desirable.

On the other hand, the mechanism can be so arranged that the oven door can be 20 readily opened and closed without interfering with or disturbing the movable bottom after it has been moved back into the oven.

I claim:

1. The combination with an oven and a 25 door, of a movable bottom, telescopic members connected with the movable bottom and rear of the oven, a crank shaft connected to one of the telescopic members, a draw bar pivotally connected to the crank shaft at one end and having its outer free end 30 connected to the oven door, whereby upon the opening and closing of the door, the movable bottom will be moved from and into the oven.

35 2. The combination with an oven and a door, of a movable bottom, telescopic members connected with the movable bottom

and rear of the oven, a crank shaft connected to one of the telescopic members, a draw bar pivotally connected to the crank shaft, a vertically adjustable latch carried by the oven door and adapted to engage the outer free end of the draw bar, whereby upon the opening and closing of the door the movable bottom will be moved from and 45 into the oven.

3. The combination with an oven and a door, of a movable bottom, telescopic members connected with the movable bottom and rear of the oven, a crank shaft connected to one of the telescopic members, a draw bar pivotally connected to the crank shaft at one end and having its outer free end 50 slidably supported upon a pin, a vertically adjustable latch carried by the door, which, when in its upper or lower position is adapted to engage or disengage the outer free end of the draw bar.

4. The combination of an oven and door, a removable bottom, a slotted bracket, an 55 extensible lever pivotally connected at one end to the movable bottom and slidably connected at the other end with the slotted bracket, a crank shaft pivotally connected with the extensible lever, a slidably pivoted draw bar pivotally connected with one end 60 of the crank shaft, a bracket connected with the oven door in position to engage a notch in the draw bar to slide the latter and actuate all its connected parts when the oven 65 door is moved.

In testimony whereof I affix my signature.

THEODORE HENRY KNORR.

Copies of this patent may be obtained for five cents each, by addressing the "Commissioner of Patents, Washington, D. C."
